Attorney

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING-MACHINE.

1,370,323.

Specification of Letters Patent. Patented Mar. 1, 1921.

Application filed September 3, 1919. Serial No. 321,307.

To all whom it may concern:

Be it known that I, ALFRED G. F. KUROWSKI, a subject of the Emperor of Germany or a citizen of Germany, but having taken out preliminary United States naturalization papers, residing in Brooklyn borough, in the county of Kings, city and State of New York, have invented certain new and useful Improvements in Typewriting-Machines, of which the following is a specification:

This invention relates to key-tops, and more especially to key-tops of typewriter keys. Such key-tops include a paper on which is printed the designation of the type or types controlled by the particular key and a glass cover serving to protect the paper. In some instances, it may be desirable to change the type papers so as to substitute others bearing different characters, or to substitute blanks. This invention, therefore, has for an object such improvement in the construction of a key-top that the key-paper thereof may be changed by an operative who is unskilled in mechanics by an extremely simple manipulation.

A feature of the invention resides in the provision of a key-cup having a slot therein of sufficient extent to permit the ready insertion and withdrawal of the key-paper, and preferably in the particular embodiment of the invention shown, this slot is normally closed by a flexible and resilient member carried by the key-ring. Preferably, also, the key-ring is made of spring-metal, so that when the resilient member thereof is moved to position to prevent withdrawal of the key-paper, said member will immediately return to normal position when released. The key-ring has a cut-away portion or slot which coincides with the slot in the key-cup, the resilient member closing both slots when in normal position.

Other features and advantages will hereinafter appear.

In the accompanying drawings,

Figure 1 is a perspective view of a key having my invention applied thereto.

Fig. 2 is a composite view with the parts in perspective, said view showing the key-cup, the key-paper and glass, and the key-ring as it would appear before it is completely formed.

Fig. 3 is a sectional view, showing the parts in the position they would occupy

when a key-paper is in the process of being withdrawn.

Fig. 4 is a view similar to Fig. 3, but with the parts in normal position.

Fig. 5 is a bottom plan view. Referring to the drawings, a key-stem 1 has mounted upon it a key-cup 2, said key-cup being slightly deeper than the usual cup, and being provided with a slot 3 extending a distance of about half of the circumference of the flange of the cup. Through this slot the key-paper 4 and key-glass 5 may be inserted and withdrawn. The key-cup is surmounted by a key-ring 6 having a bent-over top flange 7 and a lug 8 depending from the side flange, said lug 8 adapted to be bent under the bottom of the cup, as shown in Figs. 3 and 4. The ring also has a cut-away portion 9 adjacent the slot 3 of the cup to enable the insertion and withdrawal of the key-paper and key-glass.

In order to retain the key-paper and glass in position within the key-cup, and also to assist in the retention of the key-ring on the key-cup, the key-ring is provided with a member 10, which, when bent up from the position shown in Fig. 2 to the position shown in Fig. 5, will lie underneath the cup and engage the bottom thereof. Said member 10 has a lip 11, which, when bent up to the position shown in Figs. 1, 3 and 4, serves to close the slots in the ring and cup, and thereby retain the key-paper and glass in place within the cup. By reason of the fact that the key-ring is made of spring-metal, the member 10 is resilient as well as flexible, and may therefore be readily moved to the position shown in Fig. 3, and when in such position the key-paper may be readily withdrawn and a different one inserted as desired. When the paper and glass are entirely within the key-cup, as shown in Fig. 4, the resilient member 10 automatically moves to position so that the lip 11 closes the slots in the cup and the ring, and also by reason of the engagement with the bottom of the key-cup serves to hold the key-ring in place.

Variations may be resorted to within the scope of the invention, and portions of the improvements may be used without others.

Having thus described my invention, I claim:

1. A key-top comprising a key-cup for retaining a key-paper, said cup having a slot

for the insertion and withdrawal of the key-paper, and resilient means for closing said slot.

2. A key-top comprising a key-cup for retaining a key-paper, a key-ring, said cup having a slot for the insertion and withdrawal of the key-paper, and resilient means carried by said key-ring for closing said slot.

10 3. A typewriter key-top comprising a key-cup and a key-ring, said key-cup having a slot therein, said key-ring being formed of spring-metal, and having a resilient member formed as a part thereof for closing said slot.

15 4. In a typewriter key-top comprising, in combination, a key-cup for retaining a key-paper, a key-ring surmounting said key-cup, and resilient means acting to retain said key-ring in position on the key-cup and to retain the key-paper within the key-cup.

20 5. A key-top comprising a key-cup for retaining a key-paper, said cup having a slot for the insertion and withdrawal of the key-paper, and a key-ring surmounting said cup and carrying resilient means to close said slot, said means being movable to release said ring.

25 6. A key-top comprising a key-cup for retaining a key-paper, said cup having a slot for the insertion and withdrawal of the key-paper, and a key-ring surmounting said cup and having a slot coincident with the slot in the cup, said ring carrying resilient means 30 for closing said slots, said resilient means being movable to release said ring.

35 7. In a typewriter key, the combination with a key-stem, of a key-cup having a socket for mounting the cup on said stem, a key-paper and glass in said cup, said cup having a slot in its vertical circular wall to permit insertion and withdrawal of the key-

40 paper and glass, and a key-ring provided with a slot coincident with the slot in the key-cup, and having a depending prong and a resilient member adapted to engage the base of said cup, said resilient member carrying an upwardly-extending prong to close the slots.

45 8. In a typewriter key, the combination with a key-stem, of a key-cup having a socket for mounting the cup on said stem, a key-paper and glass in said cup, said cup having a slot in its vertical circular wall to permit insertion and withdrawal of said key-paper and glass, and a key-ring provided with a slot adapted to register with the slot of the key-cup, and having a depending prong and a resilient member adapted to engage the base of said cup, said 50 resilient member carrying an upwardly-extending prong to close the slots, the resilient member being movable to release said ring.

55 9. In a typewriter key, the combination with a key-stem, of a key-cup having a socket for mounting the cup on said stem, a key-paper and glass in said cup, said cup having a slot in its vertical circular wall to permit insertion and withdrawal of said key-paper and glass, and a flanged key-ring 60 provided with a slot coincident with the slot in the key-cup, and having a depending prong and a resilient member adapted to engage the base of said cup, said resilient member carrying an upwardly-extending 65 prong to close the slots, the resilient member being movable to release said ring, said flanged ring being adapted to clamp the key-paper and glass in said cup.

70 ALFRED G. F. KUROWSKI.
